US00D885821S

(12) **United States Design Patent** (10) Patent No.: **US D885,821 S**
Larsen et al. (45) Date of Patent: ** Jun. 2, 2020

(54) **FERMENTER FOR MANUFACTURE OF PROTEINS**

(71) Applicant: **UNIBIO A/S**, Odense M (DK)

(72) Inventors: **Ebbe Busch Larsen**, Odense South East (DK); **John Villadsen**, Ålsgårde (DK); **Patrick Nicklas Pederson**, Tølløse (DK); **Benny Max Moulin Grühl**, Rødvre (DK)

(73) Assignee: **UNIBIO A/S**, Odense M (DK)

(**) Term: **15 Years**

(21) Appl. No.: **29/668,826**

(22) Filed: **Nov. 2, 2018**

(30) **Foreign Application Priority Data**

Sep. 3, 2018 (EP) 005627353-0001

(51) **LOC (12) Cl.** 31-00

(52) **U.S. Cl.**

USPC **D7/368**

(58) **Field of Classification Search**

USPC D7/368, 387, 213, 398, 323, 300, 402;

D15/1-7, 9.1, 28, 199

CPC .. C12C 13/00; C12C 1/00; C12C 1/02; C12C

11/006; B01F 3/04602
